UNITED STATES PATENT OFFICE

2,156,768

LIGHTING CONSTRUCTION

George F. Niemann, Chicago, Ill., assignor to
 Benjamin Electric Mfg. Company, Chicago,
 Ill., a corporation of Illinois

Application February 24, 1936, Serial No. 65,347

2 Claims. (Cl. 240—65)

My invention relates to a lighting construction. More specifically, it relates to a fixture hanger of the type shown in the United States Letters Patent No. 2,024,331, issued December 17, 1935 to Reuben B. Benjamin, which discloses a pivotally mounted bracket, to which a lighting fixture may be detachably secured, having a pull member passing over a pulley in the bracket for drawing the fixture into proper relation with respect to the bracket.

One of the objects of my invention is to provide improved means for guiding the flexible member in the bracket having provisions whereby this path may be varied to correspond to different pivotal adjustments of the bracket.

A further object is to provide improved means for drawing the plug on the fixture into snug engagement with the socket on the bracket.

A further object of my invention is to provide a bracket construction which will be inexpensive to manufacture.

Further objects and advantages of the invention will appear from the description and claims.

In the drawings, in which my invention is illustrated,

Figure 1 is a vertical sectional view showing the pivoted bracket and a portion of the lighting fixture secured therein;

Fig. 2 is a perspective view showing the fixture, bracket-supporting pole and tightening lever; and

Fig. 3 is a detail view showing the tightening lever.

Referring to the drawings in detail, the construction shown comprises a supporting pole 1 for supporting a lighting fixture at a substantial height, a mounting bracket 2 secured to the upper end of this pole, a fixture supporting bracket 3 pivotally secured to this mounting bracket, having a downwardly-opening plug-receiving socket 4, electrical contacts 5 for engagement with contacts 6 on the fixture 7, a pulley 8 mounted on the bracket above the socket, the lighting fixture 7 comprising a lamp socket 9 for the lamp 10, a reflector 10a, and a plug 11 for engaging said socket 4, a flexible pull member 12, such as a chain secured to the plug and extending over the pulley 8 for drawing the plug into the socket, and guide means carried by the bracket for determining the path of travel of the chain with respect to the bracket having provisions whereby said path may be varied to correspond to different pivotal adjustments of the bracket.

The guide means shown comprise a pulley

14 and mounting means for the pulley adjustable in slots 15 in the bracket toward and away from the axis 16 of the bracket. This enables an adjustment to be made by means of which any one of three different paths of travel of the chain through the bracket may be obtained.

If the bracket 3 is adjusted to hold the reflector 10a at or near its lowest position, in which the chain guide 17 on the fixture will be in the position indicated in dotted lines at C in Fig. 1, the path of the chain will be as indicated at A, the chain passing over the pulley 14 between the pulley and the pivotal mounting of the bracket, the pulley 13 being set as close to the pivotal mounting 16 as the slots will permit. This tends to hold the chain 12 in alignment with the chain guide 17 and prevents interference between the chain 12 and the chain guide 17 on the reflector when the plug 11 is being pulled to its final seating position in the socket 4, enabling the plug 11 to align itself axially with respect to socket 4 without any substantial side pressure due to the pull on the chain.

In cases where it is desired that the reflector should be in its extreme raised position, in which the chain guide 17 on the reflector will be in the position indicated in dotted lines at D in Fig. 1, the path of the chain will be as indicated at B, in which the pulley mounting is set as far away from the pivotal mounting 16 of the bracket as the slots 15 will permit and the chain passes between the pulley 14 and the adjacent edge 18 of the chain housing of the bracket 3. This prevents interference between the chain guide strap 17 on the reflector and the chain itself when the plug is being pulled to its final seating position in the socket.

In cases where it is desirable that the reflector-carrying bracket 3 should be in its mid-position, the path of the chain is as indicated at E in Fig. 1, the pulley being set as far as possible from the axis of the bracket and the chain passing between the pulley and the axis of the bracket. This position of chain travel also prevents interference between the chain and the guide strap 17 when the plug is being pulled to its final seating position, enabling the plug 11 to align itself axially with respect to the socket 4.

In order to draw the plug snugly to its seat in the socket, a lever 19 is provided pivotally mounted on the bracket 20 adjustably secured adjacent the lower end of the supporting pole 1 in convenient position for operation. This lever has a laterally extending hook 21 over which a link of the chain may be passed, thus providing in

effect a pivotal connection between the lever and chain, which pivotal connection is moved past the dead center position when the lever is moved from the dotted-line to the full-line position shown in Fig. 2. When the lever has been moved to the full-line position, it may be secured against accidental displacement by means of a padlock 22 or the like, the hasp portion of which may be passed through registering openings in the 10 mounting bracket and lever. By a suitable selection of the link with which the lever is connected and a suitable adjustment of the lever carrying bracket up or down on the pole, the desired amount of tension may be placed on the spring 15 23 (Fig. 1) which forces the plug 11 into the socket 4. The vertical adjustment of the lever-carrying bracket 20 on the pole 1 is effected by the provision of slots 24 in the bracket 20 through which pass cap screws 25 which are threaded into 20 the supporting post 1. The provision of the padlock prevents accidental or unauthorized release of the fixture from the bracket.

In order to facilitate the manufacture of the bracket, it is made in two parts, one part 26 of 25 which forms a housing for the chain 12 and pulleys 8 and 14 and the other part 27 of which provides the socket 4 for the plug 11 and a skirt portion 28 for extending over the hood 29 of the reflector.

30 The spring connection between the chain 12 and plug 11 is substantially as disclosed in the aforesaid Benjamin patent and comprises the spring 23 seated in a central chamber in the plug and a pull rod 30 passing through this spring and 35 connected to the chain at 31. The upper end of the spring seats against a shoulder 32 in the plug, and the lower end seats against a washer 33 secured to the pull rod 30. Current is supplied to the contacts as in the aforesaid Benjamin patent by means of flexible cables 34 leading 40 from the conductors which extend up through the pole 1 to the contacts carried by the bracket.

The bracket 3 may be held in the desired position of pivotal adjustment by means of a bolt 35 45 passing through an opening in the bracket 3 and through slots 36 in the mounting bracket 2. The socket portion 27 of the bracket is secured to the housing portion by means of rivets 37 passing through openings in the socket portion 27 50 and the housing portion 26. This two-part construction of the bracket lessens the cost of the molding operation and of the machining operations.

In use, in lowering the fixture, a lowering 55 60 rope (not shown) is snapped onto the lower end of the chain 12, the padlock 22 is unlocked, the lever 19 is raised to the dotted-line position shown in Fig. 2, and the chain 12 can then be released from the lever. The fixture is then lowered by paying out on the rope attached to the chain 12 until the fixture is lowered to a position in which it is accessible for cleaning and removal, and replacement of parts.

In order to support the fixture in its lowered 65 70 position, a safety stop is provided which holds the fixture at the right height above the ground

for easy cleaning and servicing. This safety stop may be in the form of a stop link 38 in the chain 12, which is connected at the time of installation and determines the point to which the fixture can be lowered by engagement with the 5 lower edges of the bracket.

When the fixture has been serviced, it is raised to its position at the top of the pole simply by pulling down on the rope until the chain 12 is drawn down far enough to be again connected 10 with the lever 19. The final seating movement of the plug in the socket is then effected by moving the lever 19 from the dotted to the full line position shown in Fig. 2, and locking it in this 15 position. The lowering rope may then be un-snapped, leaving the fixture in proper operative position.

Further modifications will be apparent to those skilled in the art and it is desired, therefore, that the invention be limited only by the prior art 20 and the scope of the appended claims.

Having thus described my invention, what I claim and desire to secure by Letters Patent is:

1. A lighting construction comprising a support, a bracket pivotally secured to said support 25 to swing about a substantially horizontal axis, said bracket being provided with a downwardly-opening plug-receiving socket having electrical contacts, and a pulley mounted on said bracket above said socket, a lighting fixture having contacts for engagement with said first contacts and comprising a lamp socket, a reflector, and a plug for engaging said socket, a flexible pull member secured to said plug and extending over said pulley and thence downwardly between said fixture and said horizontal axis for drawing the plug into the socket, and guide means for said flexible pull member carried by said bracket below said pulley comprising a pulley mounted on said bracket and having space on each side 40 thereof adjacent its periphery whereby the flexible pull member may be placed on either side of said pulley.

2. A lighting construction comprising a support, a bracket pivotally secured to said support 45 to swing about a substantially horizontal axis, said bracket being provided with a downwardly-opening plug-receiving socket having electrical contacts, and a pulley mounted on said bracket above said socket, a lighting fixture having contacts for engagement with said first contacts and comprising a lamp socket, a reflector, and a plug for engaging said socket, a flexible pull member secured to said plug and extending over said pulley and thence downwardly between said 55 fixture and said horizontal axis for drawing the plug into the socket, and guide means for said flexible pull member carried by said bracket below said pulley comprising a pulley mounted on said bracket and having space on each side thereof adjacent its periphery whereby the flexible pull member may be placed on either side of said pulley, said pulley being mounted for adjustment 60 toward and from said horizontal axis.
